COSMETIC HOLDER

Leonard Abbotts, Bridgeport, Conn., assignor to
 The Bridgeport Metal Goods Manufacturing
 Company, Bridgeport, Conn., a corporation of
 Connecticut

Application October 26, 1945, Serial No. 624,730

7 Claims. (Cl. 206—56)

1

This invention relates to holders for cosmetics and the like, such, for example, as lipsticks, eyebrow pencils and so forth, and has for an object to provide a construction whereby when the closure cap or shell is in position it is not possible for someone to operate the propelling means for the stick of cosmetic or other plastic material, to jam this stick against the closed end of the closure, thus ruining the shape of the stick.

With the foregoing and other objects in view, I have devised the construction illustrated in the accompanying drawing forming a part of this specification. It is, however, to be understood the device is not limited to the specific details of construction and arrangement shown, but may embody various changes and modifications within the scope of the invention.

In this drawing:

Fig. 1 is a partial side elevation and partial section of the device with one form of the closure cap or shell in position;

Fig. 2 is a side elevation of the rotary sleeve of the propelling mechanism;

Fig. 3 is a side elevation of the stationary sleeve of the propeller;

Fig. 4 is a longitudinal section of a modified form of closure cap or shell, and

Fig. 5 is a similar section of another modified construction of closure cap or shell.

With the usual form of cosmetic holder, particularly lipstick holders, it is common when these holders are on display in a store, for a customer to pick them up and operate the propelling means, as this usually comprises a rotary hand grip exposed at the open end of the closure cap or shell. This operates the mechanism within the holder for advancing the carrier for the lipstick plastic and is likely to jam the free end of this stick against the closed end of the cap or closure, thus of course ruining the shape of the stick and rendering it unsalable. It is therefore an object of this device to make it impossible for anyone to operate the propelling mechanism for the lipstick or the like when the closure cap is in the closing position. This is done by so connecting the closure cap or shell to the casing of the holder that the cap has free turning movement on the casing, or the casing with the propelling mechanism and hand grip for operating it has free turning movement as a unit in the closure.

In the form of the device shown in the drawing the holder comprises a standard type of propelling or feeding means for the stick of cosmetic, but the invention is adapted for use with other

2

types of propelling means. The holder illustrated comprises an outer casing 10 which may be a drawn tubular shell open at both ends and in which is a stationary sleeve 11. This sleeve may be a longitudinally slit sleeve, and is ordinarily of somewhat resilient metal so that when it is inserted in the casing 10 it is compressed somewhat and, therefore, tends to expand against the casing and by frictional engagement therewith is held stationary in the casing. If desired, other or additional means may be provided for securing the sleeve in the casing. It is provided with a spiral slot 12 which forms part of the propelling mechanism. Within the stationary sleeve 11 is a rotary sleeve 13 provided with a longitudinal slot 14. Within the rotary sleeve is the carrier 15 for the stick of plastic material 16 such as lipstick, eyebrow pencil or any other material which it is desired to carry within a holder and be projected therefrom at one end for use. This carrier 15 is usually a drawn metal cup into which the lower end of the plastic stick 16 is inserted, and it carries some sort of a lateral projection, such, for example, as a pin 17, which extends into the slots 14 and 12. It will thus be seen that by rotation of the sleeve 13 the slot 14 will carry this pin along the spiral slot 12 and it will be guided along the walls of this slot to slide the carrier 15 and the plastic material 16 longitudinally in the casing and project the free end 16' thereof for use. After use it is withdrawn into the casing by rotating the sleeve 13 in the opposite direction, where it is protected, and the open end of the casing enclosed in a closure cap or shell 18. Suitable means is provided for rotating the sleeve 13, such, for example, as the hand grip 19. In the form shown this comprises a cupped member of metal or other suitable material into which the lower end 20 of the sleeve 13 is seated and to which it is attached so that the sleeve is rotated by operation of this hand grip. The sleeve may be a tight friction fit in this hand grip or other means may be provided for securing the two together, such, for example, as solder or cement if desired. The upper end of the casing 10 may be turned inwardly over the upper end of the sleeve 13, as shown at 21, to give a finished appearance and protect the end of the sleeve, and prevent the end of the sleeve from cutting or scraping plastic from the stick 16 to work down into the mechanism. The sleeve 13 may be provided with an outwardly extending bead 22 adjacent its upper end extending over the end of the fixed sleeve 11 to retain the sleeve 13 in the casing. The

lower ends of the sleeve and the casing may cooperate with the top shoulder 23 of the hand grip to limit movement in the opposite direction.

Mounted within the closure cap or shell 18 is a sleeve 24 which is held within the shell or cap by any suitable means, but has free turning movement within the cap. In the form shown in Fig. 1, the sleeve 24 is provided with an outwardly extending peripheral bead 25 extending into a groove 26 formed on the inner wall of the closure cap 18. This holds the sleeve in the cap against longitudinal movement, so that the sleeve remains in the cap when the cap or closure is removed from the casing, but the sleeve 24 is of somewhat smaller external diameter than the internal diameter of the cap 18, so that it is free to turn in the cap. However, the internal diameter of the sleeve 24 is substantially the external diameter of the casing 10, so that this sleeve has a relatively tight telescoping fit on the casing 10 and forms enough friction to retain the closure cap on the casing during normal carrying and handling operations, but permits removal of the closure cap from the casing by pulling it off the upper end thereof. If preferred, the sleeve 24 may have a free sliding fit on the casing 10 and this casing be provided with one or more friction lugs 31 lanced and bent outwardly from the casing so that its resiliency will press it against the sleeve 24 to form a friction grip to hold the closure in place.

It will be seen that in this arrangement, therefore, when the closure cap is in position on the casing it may be freely rotated with respect to the casing and the hand grip 19, or the hand grip with the casing 10 and the propelling mechanism can all be rotated as a unit within the closure cap 18. Therefore, as in order to operate the propelling mechanism for the carrier 15 it is necessary to have relative turning movement between the sleeve 13 and the casing 10, it will be impossible to provide such relative movement when the closure cap 18 is in position on the casing, because any attempt to operate or rotate the hand grip 19 while the closure cap is held in the hand will merely turn the casing and the propelling mechanism as a unit within the closure cap. Therefore, it is impossible to project the plastic lipstick 16 from the casing to jam its outer end 16' against the closed end 27 of the closure cap.

In the modification shown in Fig. 4, the closure cap or shell 28 corresponding to the cap 18 is a smooth cylindrical member in which is a sleeve 29 extending substantially the full length of the member 28 but has an external diameter slightly smaller than the internal diameter of the member 28, so that it is free to turn therein. The open or lower end of the outer member 28 is turned inwardly over the lower end of the sleeve 29, as shown at 30, so as to retain the sleeve within the member 28, and longitudinal movement in the opposite direction is limited by the closed end of the member 28 cooperating with the opposite end of the sleeve 29. The inner diameter of the sleeve 29 is substantially that of the outer diameter of the casing 10, so that when this closure cap is telescoped over the casing 10 in place of the closure 18 the sleeve 29 has a close telescoping fit with the casing 10, so as to retain the closure 28 in position on the casing, or, if desired, the sleeve 29 may have a free sliding fit on the casing 10 and the one or more spring friction ears 31 lanced and pressed slightly outward from the casing 10 will form

the necessary friction grip on the sleeve 29 to retain the closure in place on the casing. It will be apparent that when this closure cap is in position on the casing 10, the sleeve 29 will be held stationary with respect to the casing 10 while the outer member 28 is free to rotate, in the same manner as described for the member 18, and, therefore, it will be impossible to operate the hand grip 19 to operate the propelling mechanism to jam the lipstick against the closed end of this closure.

Fig. 5 shows another modified construction of the closure cap or shell, and while this may be used with a metal closure cap it is adapted primarily for use with a molded plastic form of cap. The closure cap or shell 32 may be molded from a suitable plastic material, such, for example, as "Bakelite" or similar materials, and is provided at its lower open end with a tapered or inclined wall 33. Mounted in this open end is a stationary sleeve or lining 34, preferably of metal, having a close fit with the member 32 and at its lower end folded around the free edge of the outer member 32 and over the inclined surface 33, as shown at 35. This retains the member 34 permanently in the member 32. Mounted within the member 32 and sleeve 34 is a sleeve 36 whose outside diameter is slightly less than the internal diameter of the sleeve 34, so that it is free to turn in the sleeve 34. It is held against longitudinal movement in the member 32 by outwardly extending shoulders 37, 38 at its opposite ends cooperating with the opposite ends of the sleeve 34. The internal diameter of this rotatable sleeve 36 has a close telescoping fit with the sleeve 10 or the lugs 31, so that it is removably held in position on the sleeve 10, the same as the other two forms of closures, but as the sleeve 36 is free to rotate within the outer member 32 it will be evident it will be impossible by turning the hand grip 19 to operate the propelling mechanism to force the free end of the lipstick 16 against the free end of the closure, for the same reasons as described with the other forms of closures.

It will be evident from the above that in all three forms of closure the outer member of the closure is free to turn with respect to the casing 10 and other mechanism of the holder and, therefore, although the hand grip 19 may be rotated within the closure cap, it will be impossible to operate the propelling mechanism to force or jam the free end of the lipstick against the closed end of the closure cap.

Having thus set forth the nature of my invention, what I claim is:

1. A holder of the character described comprising a casing open at one end, a carrier for a stick of plastic movable longitudinally in the casing, a rotatable hand grip at the other end of the casing, means operated by relative turning movements of the hand grip for shifting the carrier, a removable closure cap telescoped over the open end of the casing, a sleeve in the cap having free turning movements in the cap and adapted to telescope over the casing with a relatively tight frictional engagement therewith to retain it on the casing, and a cooperating peripheral bead and groove on the sleeve and cap arranged with the groove enclosing the bead to retain the sleeve against longitudinal movement in the cap so that the sleeve will removably retain the cap on the casing to close the open end of the casing and on removal of the cap from the casing the sleeve will be removed with it.
2. A holder of the character described com-

prising a casing open at one end, a carrier for a stick of plastic movable longitudinally in the casing, a rotatable hand grip at the other end of the casing, means operated by turning movements of the hand grip for shifting the carrier, a removable closure cap telescoped over the open end of the casing, a sleeve in the cap having free turning movements in the cap and adapted to telescope over the casing with a relatively tight frictional engagement therewith to retain it on the casing, said sleeve being substantially the full length of the cap, and the open end of the cap being turned over the outer end of the sleeve to form a flange to retain the sleeve in the cap.

3. A holder of the character described comprising a casing open at one end, a carrier for a stick of plastic movable longitudinally in the casing, a rotatable hand grip at the other end of the casing, means operated by turning movements of the hand grip for shifting the carrier, a removable closure cap telescoped over the open end of the casing, a sleeve in the cap having free turning movements in the cap and adapted to telescope over the casing with a relatively tight frictional fit to retain it on the casing, said cap being formed of molded plastic, a sleeve fixedly mounted in the cap, and cooperating means on the rotatable and fixed sleeves to retain the rotatable sleeve in the cap.

4. A holder of the character described comprising a casing open at one end, a carrier for a stick of plastic movable longitudinally in the casing, a rotatable hand grip at the other end of the casing, means operated by turning movements of the hand grip for shifting the carrier, a removable closure cap of molded plastic telescoped over the open end of the casing and provided with a tapered surface at its free end, a sleeve fitted in the open end of the cap and having its outer end fitting over the tapered surface on the cap to retain the sleeve in the cap, a second sleeve mounted for free turning movements in the first sleeve and of a size to telescope over the casing with a relatively tight frictional fit to retain it on the casing, and said rotatable sleeve being provided with outwardly extending shoulders cooperating with the opposite ends of the fixed sleeve to retain the rotatable sleeve in position in the cap.

5. A holder of the character described comprising a casing open at one end, a carrier for a stick of plastic movable longitudinally in the casing, a rotatable hand grip at the other end of the casing, means operated by relative turning movements of the hand grip for shifting the carrier, a removable closure cap telescoped over the open end of the casing, a fixed sleeve mounted in the cap adjacent its open end, a second sleeve mounted for free turning movements in the first sleeve and of a size to telescope over the casing

with a relatively tight frictional fit to retain it on the casing, and shoulders adjacent the opposite ends of the rotatable sleeve cooperating with the ends of the fixed sleeve to retain the rotatable sleeve in the cap.

5 able sleeve in the cap.

6. A holder of the character described comprising a casing open at one end, a carrier for a stick of plastic movable longitudinally in the casing, a rotatable hand grip at the other end of the casing, means operated by turning movements of the hand grip for shifting the carrier, a removable closure cap telescoped over the open end of the casing, a sleeve in the cap having free turning movements in the cap and adapted to telescope over the casing with a relatively tight frictional engagement therewith to retain it on the casing, one of said members comprising the sleeve and cap being provided with transversely extending portions at its opposite ends forming stops extending over portions of the other members to retain the sleeve against longitudinal movement in the cap so that the sleeve will removably retain the cap on the casing to close the open end of the casing and on removal of the cap from the casing the sleeve will be removed with it.

7. A holder of the character described comprising a casing open at one end, a carrier for a stick of plastic movable longitudinally in the casing, a rotatable hand grip at the other end of the casing, means operated by turning movements of the hand grip for shifting the carrier, a removable closure cap telescoped over the open end of the casing, a sleeve in the cap having free turning movements in the cap and adapted to telescope over the casing with a relatively tight frictional engagement therewith to retain it on the casing, said closure cap being provided with transversely extending portions forming stops extending over portions of the sleeve to retain the sleeve against longitudinal movement in the cap so that the sleeve will removably retain the cap on the casing to close the open end of the casing and on removal of the cap from the casing the sleeve will be removed with it.

MOVED WITH IT.
